UNITED STATES PATENT OFFICE

ARTHUR F. FORTIER, OF SAN JOSE, CALIFORNIA

DISPLAY DEVICE

Application filed October 5, 1932. Serial No. 636,284.

The present invention relates particularly to that type of display devices used for both displaying and dispensing advertising matter such as leaflets and pamphlets of various kinds.

It is one object of the invention to provide a device of the nature indicated that may be quickly and easily mounted upon the top of a container or an assembled and prearranged group of containers.

It is another object to provide a means of the character indicated that will be economical to manufacture, simple in form and construction, light in weight, strong, durable, and highly efficient in its practical application.

In the drawing:

Figure 1 is a perspective illustration of one embodiment of the invention mounted upon a can.

Figure 2 is a perspective view of another embodiment of the invention mounted upon a carton, a portion of which is broken away.

Figure 3 is a perspective view of still another embodiment of the invention mounted upon an assembly of packages, portion of which is broken away.

In the embodiment of the invention as disclosed in Figure 1, I show a single wire having an intermediate portion bent into identical, opposed, outwardly curving segments 1—1, the corresponding ends of these segments being turned backwardly and inwardly toward each other as shown at 2—2, then upwardly as at 3—3, the connecting portion 4 being thereby raised above parts 1—1 and forming the central portion of a foot-piece functioning in the manner hereinafter described.

The ends of segments 1—1 remote from parts 2—2 are likewise turned inwardly and toward each other as at 5—5, but they are also turned toward parts 2—2 as shown, and then upwardly to form upstanding back parts 6—6, thence outwardly in opposite di-

rections as at 7—7, thence forwardly in parallel relation to each other as at 8—8, finally terminating in two relatively short fingers 9—9 paralleling parts 7—7.

The result of this formation is that the natural resiliency of the wire enables the parts 1—1 to be sprung over the beaded top edge of a can as 10, the parts 2—2 and 5—5 forming stops that seat on the top of the can, or its edge, and cooperate with parts 1—1 to hold the device securely and firmly in position.

With the device mounted in this manner the parts 6—6, 7—7, 8—8, 9—9 form a pocket 11 in which the printed matter may be disposed, the can itself forming the support therefor, the wire structure indicated, together with the foot-piece 3—3, 4, serving merely to support it in an upright position.

In Figure 2 is shown a device adapted for use on a square ended carton. In this instance the central portion of the wire parallels the side of the carton 12 as at 13—13, then is bent at right angles to form opposing parts 14—14 adapted to seat against the front surface of the carton, then is bent upwardly at right angles as at 15—15, then again at right angles but inwardly as at 16—16 to overlie the top of the carton, and then upwardly at right angles as at 17—17 to form, with the connecting portion 18, a foot-piece for supporting the bottom ends of the printed matter held.

The ends of parts 13—13 remote from parts 14—14 are bent into parallel relation to parts 14—14 as at 19—19 to seat against the back of the carton, and are then turned upwardly as at 20—20 and then forwardly as at 21—21 in opposed relation to parts 16—16, thence upwardly again to form upstanding back pieces 22—22, the top of the pocket 23 being formed by bending the two ends of the wire as shown at 24—24, 25—25, 26—26 and particularly described in con-

nection with the embodiment shown in Figure 1.

In this second embodiment the parts 16—16 and 21—21 function as stops to hold the device in the desired position relative to the top of the carton, here as in the first case, the carton functions as a support for the printed matter, the wire structure serving only to support it in a substantially vertical position.

To adapt the device to certain forms of packages which are too small to support a package of advertising or display matter individually, I construct it in the following manner, as clearly shown in Figure 3.

In this case two packages are set side by side as at 27, and a third package 28 is positioned as shown. Since the packages are oblong in form the package 28 projects above the other two.

The wire in this case has the intermediate portion disposed with parts as 29—29 seated against the opposite ends of packages 27 in parallel relation to their top surfaces, the connecting portion being bent upwardly as at 30—30 and curved inwardly over the top of a package 27 to form loops as 31—31 which function as foot-pieces, thence forwardly as at 32—32 to form stops, thence downwardly again as at 33—33 against the forward side of the front carton 27, thence forwardly as at 34—34 to embrace the sides of package 28, the connecting central portion 35 engaging the front surface of package 28.

The ends of parts 29—29 remote from parts 30—30 are bent toward each other as at 36—36 to embrace the back of the rear package 27, thence upwardly as at 37—37, thence forwardly as at 38—38 to overlie the top of the package 27 and form stops, thence upwardly again to form upstanding back-pieces 39—39 which terminate in bends 40—40, 41—41, 42—42 forming the top portion of a pocket 43 as heretofore described.

It is to be understood, of course, that while I have herein shown and described but certain specific embodiments of the invention, changes may be made in form, construction, and method of arrangement and application within the scope of the appended claims.

I claim:

1. A device of the character described comprising a wire bent and formed to partially encompass a container and having portions thereof bent and formed to overlie the container to form stops seating thereon, a portion of the wire being bent upwardly to form a foot-piece adjacent one edge of the container, and another portion of the wire being bent and formed into an upstanding support forming a pocket adjacent another edge of the container.

2. A device of the character described com-

prising, a wire having portions between its center and two ends bent into opposed relation to each other to engage the two sides of a container, the portion of the wire including its center being bent to form stops adapted to engage the top of the container and to form an upstanding foot-piece, and the portions including the two ends being bent to form stops adapted to engage the top of the container and to form a pocket for the reception of printed matter.

3. A device of the character described comprising, a wire having intermediate spaced parts bent to form opposed arcuate portions adapted to engage the opposite sides of a container, the portion between the arcuate portions being bent back upon itself to form stops adapted to engage the top of the container and then upwardly to form a foot-piece, and the two end portions being bent back upon themselves to form stops adapted to engage the top of the container, thence upwardly to form a back rest, thence outwardly in opposite directions and forwardly in parallel relation to each other and inwardly toward each other to form a pocket.

4. A device of the character described comprising, a wire having spaced intermediate parts bent into parallel relation to each other to engage the sides of a container, the portion between said parts being bent at right angles thereto to engage the front of the container and then upwardly at right angles and inwardly at right angles to form stops adapted to engage the top of the container and then upwardly to form a foot-piece, the two end portions being bent at right angles toward each other to engage the back of the container and then upwardly and forwardly to overlie the top of the container to form stops adapted to engage its top, thence upwardly to form a back rest, the ends of the wire being bent into symmetrically formed oppositely disposed recesses to form a pocket for the reception of printed matter.

5. A display device for mounting upon an assembly of packaged goods where one package is narrower than the others, comprising a wire having a straight central portion adapted to engage the face of the narrow package, the two ends being bent backwardly to engage the sides of the package, thence upwardly to the top of the wider packages, thence backwardly to form stops overlying the wider packages, thence upwardly, outwardly and downwardly on the sides of the wider packages to form foot-pieces, thence backwardly and inwardly to engage the backs of said packages, thence upwardly and forwardly to overlie the same and form stops to engage the tops of the packages, thence upwardly to form a back rest, the terminals of the wires being bent and formed

into opposing loops to form a pocket for the reception of printed matter.

6. A display device of the character indicated comprising, a wire having its central portion bent to partially encompass packaged goods and bent to engage over its top with an upstanding portion adapted to form a foot-piece, the ends of the wire also being bent to engage over the top of the package and being bent upwardly to form a back rest, the terminals of the wire being bent into opposing guides to form a pocket.
